UNITED STATES PATENT OFFICE

2,453,977

CARTRIDGE FEEDING DEVICE

James Owen Eames, Washington, Conn., assignor
to Roy S. Sanford, Woodbury, Conn.

Application March 28, 1946, Serial No. 657,803.

8 Claims.

(Cl. 89—33)

1

This invention relates to automatic guns, and particularly to guns of the class in which the cartridges are fed to the gun gripped in links forming a flexible belt, the belt being of the "disintegrating" type.

Guns of the aforesaid type are well known. Each cartridge is gripped in resilient fingers forming parts of a link, a plurality of such links being flexibly interconnected to form a belt. The latter is stored in a suitable magazine placed adjacent the gun, and the belt is fed in a step-by-step movement by suitable mechanism forming part of the gun, and by means of which movement each link and the cartridge gripped thereby are positioned in predetermined relation to the chamber or breech ready for stripping of the cartridge and the chambering thereof. The devices for feeding each cartridge into such predetermined relation to the chamber may be operated by any of several well-known means, either by the recoil of the exploded charge, by pneumatic or hydraulic means, electrically or otherwise. In any event, a pawl or similar element adapted to engage the links seriatim is given the necessary reciprocating movement for feeding the belt.

In certain prior guns, attempts have been made to insure proper positioning of the link and its individually gripped cartridge in proper relation to the chamber by the use of antiback-lash devices designed to overcome the surge of the belt due to momentum thereof under rapid-fire conditions; for example, by the use of a spring-pressed lever bearing on the top of the link to force portions of the latter into a slot in the floor of the cartridge feedway, from which position the cartridge is stripped. Such means has proved unsatisfactory because of the likelihood of the momentum of the belt overcoming the tension of the spring and overriding the slot. In such case the cartridge is moved off-center with respect to the stripping device and misfiring or jamming results.

My invention accordingly has for a principal object the provision of means for positively seizing the link on both sides thereof, and preferably at a time when the cartridge is approaching stripping position, which means is unaffected by the momentum of the belt, to position the link accurately in predetermined relation to the chamber and the cartridge-stripping device.

Another object is to provide means as aforesaid having its parts so constructed and arranged as to be capable of ready adaptation to

2

a common type of gun with little alteration in pre-existing parts.

Still another object is to provide link-positioning and holding means which will not only 5 position the link in the manner aforesaid, but will maintain such position during the stripping operation.

A further object is to combine in the link-positioning and holding means elements which 10 are effective to maintain downward, as well as longitudinal, positioning of the link to prevent axial displacement of the link during stripping.

Other and further objects will become apparent as the description proceeds.

15 My invention will, for convenience, be described as applied to a gun utilizing a rotary sleeve actuated by the reciprocation of the bolt, the sleeve having gear teeth engaging a rack carrying the belt-feeding pawls. It will be understood, however, that the invention is capable 20 of being embodied in guns otherwise constructed, except that they shall include some kind of reciprocable member for feeding the links seriatim to the gun and a slot or equivalent co-aligning 25 means wherein certain parts of the link are adapted to lie to position the link for the stripping operation. Accordingly, in carrying out the invention in one form, I provide a member 30 slidable with respect to the rack, the member having an inclined cam surface or surfaces 35 adapted to abut and, during certain phases of the cycle, to impart a camming action to the link. Resilient means, e. g., a compression spring, is provided intermediate the rack and the slidable member to cause joint movement 40 therebetween during predetermined portions of the cycle and to permit relative movement therebetween at other times, and a positive stop is interposed between the rack and member to limit 45 said relative displacement therebetween. The cam surface is co-operative with the pawl or pawls to grip the link therebetween to feed the latter positively to a position in axial alignment with the breech during the feeding stroke of the 50 rack, and immediately thereafter to thrust the link downwardly to engage the cartridge gripping fingers thereof with the edges of the feedway slot, through which opening the cartridge is moved after stripping thereof. Following the stripping operation, the cam surface is released from the link to permit the latter to be moved out of engagement with the slot upon the feeding of a succeeding link.

In the drawings, which show a preferred form 55 of my invention:

Fig. 1 is a somewhat diagrammatic cross-sectional view taken transversely of the gun, and principally just to the rear of the belt of cartridges, and showing the first step of a cycle of operations;

Figs. 2 through 9 are views similar to those of Fig. 1 showing succeeding steps in the cycle;

Fig. 10 is a cross-sectional view taken longitudinally of the gun and substantially on the line 10—10 of Fig. 1; and

Fig. 11 is an exploded perspective view showing the several principal parts constituting the essence of the invention.

Referring to Figs. 1, 10, and 11, there are shown the pertinent portions of a gun in which my invention may be embodied and including the cartridge feedway 11, the receiver 12, and the bolt 13, the latter being indicated schematically. The feedway 11 is substantially an open-sided box-like structure having a floor 21, a front wall 22, a rear wall 23, and a cover 24, the latter being constituted in part by the feeder assembly 25. The floor 21 has an elongated slot 26 disposed axially of the gun and having chamfered margins 27 (Fig. 1) to receive certain parts of the cartridge link 31 to be hereinafter detailed, the contour of the edges of the slot being such as to permit the stripped cartridge to pass through the slot into the receiver with its axis inclined to the horizontal, and upon passing into the receiver to be picked up by the advancing bolt 13 for chambering of the round 32.

The rounds are carried to the feedway 11 from a magazine (not shown) by inserting each round 32 in an individual link 31 of a well-known type, for example, as shown and described in the co-pending application of Roy S. Sanford and John J. Murphy bearing Serial Number 542,559 and filed June 28, 1944, which has now matured into Patent Number 2,426,527, granted August 26, 1947. Links 31 are connected into a flexible belt by interengaging portions (not shown), it being understood that feeding movement imparted to a link will feed the remaining links to and through the feedway 11.

Step-by-step movement is imparted to the cartridge belt by feed pawls 33 (Fig. 11) bridged by a member 34, and therefore operable together. Compression spring 35 constantly urges pawls 33 into feeding relation with respect to a link while permitting yielding thereof upon return movement of the pawls. It is to be noted that in Figs. 1 through 9, pawls 33 are, for reasons of clarity, shown diagrammatically.

To maintain the belt against backlash to some extent, a pair of belt holding pawls 36 is provided, which pawls have, for clarity, been shown as a single pawl below the links. However, the effects of pawls 36 would be the same whether positioned above or below the links. For convenience of assembly and operation, they are, in the gun itself, located within the housing 37 and hence above the links. It will appear from what follows that pawls 36 are only accessory to the link engaging means forming the principal subject matter of the invention.

Feed pawls 33 are pivoted at 41 to the belt feed rack 42, the latter comprising a generally elongated body having laterally extending flanges 43 slidable in grooves 44 transversely of the framework 47 forming part of the feeder 25. On its upper face the rack 42 is provided with teeth 45 in mesh with teeth 48 cut in the periphery of the belt feed tube 46 (Fig. 1). Tube 46 is provided with a helical slot engaged by a roller

(both not shown) protruding from the bolt 13. Thus upon reciprocation of the bolt, the tube 46 will be rotated alternately clockwise and counter-clockwise to actuate the rack 42 to the left for feeding and to the right for return, in synchronism with the strokes of the bolt.

Slidably secured to the rack 42 is the stripper 51 (Fig. 11) comprising an elongated body having laterally extending flanges 52 slidable in corresponding grooves 53 in the rack 42 and a pair of camming elements 54 having inclined working faces 55 and horizontal working faces 56. It will be noted that the horizontal faces 56 are substantially semicircular in transverse contour (Fig. 10) for a purpose to appear.

Disposed in grooves 61 in the upper face of the stripper 51 is a pair of pins 62 encircled by compression springs 63 bearing at one end against the pins 64 fitted into the underside of the rack 42, and at the other end against the heads 65 of the pins 62, the heads in turn bearing against the flattened faces 66 of the pin 67 screwed into a suitable aperture in the stripper 51. Movement of the stripper 51 relatively to the rack 42 under influence of the interposed springs 63 is restrained in one direction by engagement of the pins 64 against the semicylindrical end faces 68 of the grooves 61.

Stripper 51 is so disposed longitudinally with respect to the feedway 11 as to effect an engagement of either the surfaces 55 or 56 with predetermined portions of the link 31 (Fig. 10), it being noted that the protruding substantially central portion 40 of the link lies intermediate the elements 54 whereby the link may be held against axial movement while the cartridge is being stripped therefrom, the rounded edges of the faces 56 minimizing friction and facilitating engagement of the forward face 56 with the depressed zone 60 of the link. However, during passage from the entrance to the feedway to stripping position, the round is limited to an axial position fixed by the walls 22 and 23 abutting the tip and base of the round respectively, there being just sufficient clearance to permit feeding of the round without undue play.

Before proceeding to a description of the operation of the device, reference is made to Fig. 5 in which the link 31 is shown in proper relation to the margins 27 of the slot 26 for stripping of the cartridge. It is to be noted that the portions 70 of the link embrace or grip the casing of the cartridge and that the chamfer of the margins 27 is congruent with the outer surface of the portions 70. Thus when the link and cartridge have been brought to a position directly over the feedway, downward thrust by the stripper, as will be detailed, will engage the portions 70 within the slot, as shown, to fix laterally the link and cartridge, and from which fixed position the round may be stripped endwise and forwardly of the link as the bolt moves forward to engage the base of the round. Simultaneously the elements 54 (Fig. 10) prohibit axial movement of the link relatively to the cartridge.

Referring now to Figs. 1 through 9, there is shown a series of views depicting successive steps in the operation. In Fig. 1 the bolt is closed; i. e., a previous round has been chambered and detonation is occurring. Alternatively the bolt may be closed without a round being in the breech. The succeeding rounds, numbered 1, 2, 3, etc., of a replacement belt, are shown feeding from the right, the link 31 being about to be contacted by pawls 33 for feeding. Round 1 is held

against movement to the left by elements 54, the stripper 51 being in turn held against pins 62 engaging rack 42, the latter being restrained by the teeth of tube 46. Thus, assuming that the gun were being initially loaded, it would be impossible to insert the belt in the feedway with round 1 over the slot 26. Accordingly, no round is in the feedway slot and the gun may be initially charged without causing a jam, as is understood in the art.

Assuming, for clarity, that the gun is being initially charged, the bolt 13 is moving back (Fig. 2), the springs 63 retaining elements 54 against link 31. During this time the tube 46 is being rotated clockwise by the bolt, as described, and rack 42 is being reciprocated to the left to cause pawls 33 to feed round 1 in the same direction, i.e., toward the slot 26.

In Fig. 3 round 1 is now on top of the bolt 13, but the bolt is continuing to move to the rear. From Figs. 2 and 3 it will be seen that link 31 is constantly and positively held, being pinched between elements 54 and pawls 33.

Bolt 13 (Fig. 4) has now cleared round 1 and will continue for a short distance therebeyond to complete the actuation of rack 42. Just prior to the end of the left stroke of rack 42, stripper 51 abuts the left-hand wall of the housing 37, and cam faces 55 begin to force link 31 downwardly. Further movement of rack 42 will complete the camming action, and link 31 will be forced into engagement with slot 26 as described. Such phase is shown in Fig. 5, at which time the gun is fully charged; the bolt 13 is held back by the sear (not shown); the pawls 33 have completed full travel to the left, and round 1 is in the slot 26. It will be noted that the camming of the link 31 into the slot 26 has permitted the surfaces 56 to pass over the link under the force of springs 63, and in which position the stripper is effective to hold the link and round in position for the stripping of the latter.

To fire the gun, operation of the trigger (not shown) releases the sear to permit the bolt to move forward (Fig. 6) under urging of its driving spring (not shown). Round 1 is engaged by the bolt, stripped from its link and passed through slot 26 into the receiver for chambering by the bolt. It will be recalled that slot 26 is wider forwardly of the cross section illustrated to permit inclined transit of the round therethrough.

Forward movement of the bolt reversely rotates tube 46 to actuate rack 42 to the right. Inclined surfaces 55 of stripper 51 abut link 31a, and continued movement of rack 42 to the right carries pawls 33 over round 2, spring 35 yielding meanwhile, and springs 63 being compressed. During the stripping of round 1, elements 54 may either be held temporarily by friction against the link 31 or may move with the rack 42 until surfaces 55 abut link 31a as aforesaid.

Referring to Fig. 7, round 1 is chambered and stripper 51 is held against round 2 by springs 63. Bolt 13 is forward and locked ready for firing. Fig. 7 represents the parts of the gun in the same positions indicated in connection with Fig. 1.

Referring to Fig. 8, round 1 has been fired and the bolt 13 is moving back. Pawls 33 move round 2 toward slot 26 while empty link 31 is moved to the left toward the ejection chute (not shown) by link 31a. The parts of the device are now in the positions of Fig. 2. Succeeding portions of the cycle are the same as described in connection with Figs. 3 and 4.

In Fig. 9 the bolt is back and round 2 is in the feedway slot, the situation being the same as in Fig. 5. During automatic fire the phases of the cycle repeat those shown and described in Figs. 5, 6, 7, 8, and 9.

One important advantage of my invention over prior devices resides in its instant adaptability to right- or left-hand feed. Depending upon the way it is desired to mount the gun, it may be necessary to feed from the left-hand side or the right-hand side thereof. Some prior devices were subject to such conversion only by installing another set of certain of the parts designed for one or the other "hand," thereby complicating manufacturing and inventory problems. Contrasted with this, the rack 42 and stripper 51 are symmetrical and may be interchanged from one side of the feedway to the other for right- or left-hand feed.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

1. In an automatic gun adapted to fire cartridges carried to the gun by gripping links comprising a flexible belt, the combination comprising a feedway for the belt, said feedway having a slot defined by edges in said feedway for engagement with a portion of each link, means for feeding the belt in a step-by-step movement to position each link and its gripped cartridge in alignment with said slot, and means for moving said link into interlocked relation with the edges of said slot and maintaining said relation during stripping of the cartridge from the link for chambering thereof, said last mentioned means including a member carried by, and slidable with respect to said feeding means and having a cam surface for engagement with the link whereby to force said link to slot edge-engaging position.

2. In an automatic gun adapted to fire cartridges carried to the gun by gripping links comprising a flexible belt, the combination comprising a feedway for the belt, said feedway having a slot defined by edges in said feedway for engagement with a portion of each said link, means for feeding the belt in a step-by-step movement to position each link and its gripped cartridge in alignment with said slot, and means for moving said link into interlocked relation with the edges of said slot and maintaining said relation during stripping of the cartridge from the link for chambering thereof, said last mentioned means including a member carried by and slidable with respect to said feeding means and having at least one sloping element for camming the link to slot edge-engaging position.

3. In an automatic gun adapted to fire cartridges carried to the gun by gripping links comprising a flexible belt, the combination comprising a feedway for the belt, said feedway having a slot defined by edges in said feedway for engagement with a portion of each said link, means for feeding the belt in a step-by-step movement to position each link and its gripped cartridge in alignment with said slot, and means under the control of said feeding means and the link for moving said link into interlocked relation with the edges of said slot and maintaining said relation during stripping of the cartridge from

the link for chambering thereof, said last mentioned means including a member carried by and slideable with respect to said feeding means and having at least one sloping element for camming the link to slot edge-engaging position, and a resilient member intermediate said member and feeding means for permitting movement of said member upon actuation thereof by the fed link and for urging said member to normal position during said camming action.

4. In an automatic gun adapted to fire cartridges carried to the gun by gripping links comprising a flexible belt, the combination comprising a feedway for the belt, said feedway having a slot defined by edges in said feedway for engagement with a portion of each link, means for feeding the belt in a step-by-step movement to position each link and its gripped cartridge in alignment with said slot, and means under the control of said feeding means and the link for moving said link into interlocked relation with the edges of said slot and maintaining said relation during stripping of the cartridge from the link for chambering thereof, said last mentioned means including a member carried by and slideable with respect to said feeding means and having at least one sloping element for camming the link to slot edge-engaging position, a resilient member intermediate said member and feeding means for permitting movement of said member upon actuation thereof by the fed link and for urging said member to normal position during said camming action, and a rigid element intermediate said member and feeding means for limiting relative sliding movement of said member with respect to said feeding means upon said actuation by the link.

5. In an automatic gun adapted to fire cartridges carried to the gun by gripping links comprising a flexible belt, the combination comprising a feedway for the belt, said feedway having a slot defined by edges in said feedway for engagement with a portion of each link, a slide including a link feeding pawl, means for reciprocating said slide for presenting each link and its gripped cartridge successively to a position in alignment with said slot, and a member slidably supported on said slide and having link-engaging elements for forcing the link into engagement with the edges of said slot and maintaining said engagement during stripping of the cartridge from the link.

6. In an automatic gun adapted to fire cartridges carried to the gun by gripping links comprising a flexible belt, the combination comprising a feedway for the belt, said feedway having a slot defined by edges in said feedway for engagement with a portion of each said link, a slide including a link feeding pawl, means for reciprocating said slide for presenting each link and its gripped cartridge successively to a position in alignment with said slot, a member slidably supported on said slide and having elements engageable by the link for forcing the link into engagement with the edges of said slot and maintaining said engagement during stripping of the

cartridge from the link, and a resilient element intermediate said slide and member for permitting yieldable sliding movement therebetween upon engagement of said elements by the fed link, the member imparting force to the link after said resilient element has been stressed beyond a predetermined value.

7. In an automatic gun adapted to fire cartridges carried to the gun by gripping links comprising a flexible belt, the combination comprising a feedway for the belt, said feedway having a slot defined by edges in said feedway for engagement with a portion of each link, a slide including a link feeding pawl, means for reciprocating said slide for presenting each said link and its gripped cartridge successively to a position in alignment with said slot, a member slidably supported on said slide and having elements engageable by the link for forcing the link into engagement with the edges of said slot and maintaining said engagement during stripping of the cartridge from the link, a resilient element intermediate said slide and member for permitting yieldable sliding movement therebetween upon engagement of said elements by the fed link, the member imparting force to the link after said resilient element has been stressed beyond a predetermined value; and a stop intermediate said slide and member for limiting relative movement therebetween upon feeding movement of a link against said member.

8. In an automatic gun adapted to fire cartridges carried to the gun by gripping links comprising a flexible belt, the combination comprising a feedway for the belt, said feedway having a slot defined by edges in said feedway for engagement with a portion of each link, a slide including a link feeding pawl, means for reciprocating said slide for presenting each said link and its gripped cartridge successively to a position in alignment with said slot, and a member slidably supported on said slide and having link-engaging elements for forcing the link into engagement with the edges of said slot and maintaining said engagement during stripping of the cartridge from the link, at least one of said link-engaging elements being also adapted to cooperate with a mating portion of the link to maintain a predetermined longitudinal position of the link during stripping.
